Des. 212,774
Patented Nov. 19, 1968

212,774

DECORATIVE CHAIN LINK

Salvatore Minicucci, North Providence, R.I., assignor to Prochain, Inc., a corporation of Rhode Island

Filed Apr. 11, 1967, Ser. No. 6,639

Term of patent 14 years

(Cl. D45—16)

FIG. 1

FIG. 2

FIG. 3

FIG. 4

FIG. 1 is a top plan view of a decorative chain link showing my new design;

FIG. 2 is a side elevational view thereof;

FIG. 3 is an end elevational view thereof as seen from the right of FIG. 2; and

FIG. 4 is a perspective view thereof on an enlarged scale.

I claim:

The ornamental design for a decorative chain link, substantially as shown.
